UNITED STATES PATENT OFFICE.

EDWIN TAYLOR, OF NEW YORK, N. Y., ASSIGNOR TO TAYLOR HERRICK
ROTARY ENGINE COMPANY, A CORPORATION OF NEW YORK.

ROTARY ENGINE.

No. 831,120.

Specification of Letters Patent.

Patented Sept. 18, 1906.

Application filed March 16, 1906. Serial No. 306,458.

To all whom it may concern:

Be it known that I, EDWIN TAYLOR, a citizen of the United States, and a resident of New York city, borough of Brooklyn, county 5 of Kings, and State of New York, have invented certain new and useful Improvements in Rotary Engines, of which the following is a specification.

My invention relates primarily to rotary engines, although it may be usefully applied to pumps.

It has for its object to overcome difficulties incident to that class of apparatus in which an eccentric barrel is used in connection with a shaft provided with a piston extending through the barrel.

The parts of the apparatus are constructed as fully set forth hereinafter and as illustrated in the accompanying drawings, in 20 which—

Figure 1 is a vertical section transverse to the shaft, illustrating one construction employing my invention. Fig. 2 is a sectional elevation on the line 2 2 of Fig. 1. Fig. 3 is a 25 sectional elevation transverse to the shaft of an engine in which the details of the engine are somewhat differently constructed and arranged. Fig. 4 is a vertical section on the line 4 4 of Fig. 3. Fig. 5 is a sectional plan 30 on the line 5 5 of Fig. 3. Fig. 6 is a transverse section of the rocking bearing on the line 6 6 of Fig. 4. Fig. 7 is an edge view of the barrel. Figs. 8, 9, and 10 show three different modifications of the passages *t*. Fig. 11 is a section showing a means of compensating for wear of the piston-bearing. 35 Figs. 12 and 13 are vertical sections of the apparatus as used for transmitting motion to a fluid, as in a pump, the sections respectively coincident with the longitudinal axis and transverse of the apparatus.

Referring in the first place to the form shown in Figs. 1 and 2, the cylinder or casing *A* of any suitable form and proportions 40 contains a circular chamber *X*, concentrically through which chamber extends a shaft *B*, having a hub or enlargement *1*, from which a piston *C*, forming a part thereof, extends to the circular wall *x* of the chamber *X*. The end walls or heads of the chamber *X* may be considered as forming part of the cylinder or casing. Within the chamber *X* is a ring or barrel *D*, extending from head to head of the casing *A* and inclosing the cham-

ber *Z*. The periphery of the barrel *D* is a 55 true circle, which intersects the circle of the wall *x*, so as to occupy a recess *y*, which recess is preferably formed to correspond to the curvature of the periphery of the barrel *D*, thereby extending the contact area of the 60 meeting surfaces of the barrel periphery and casing. About midway between the ends of the recess *y* is a transverse socket for the packing-strip *2*, which extends approximately across the barrel and may contain a 65 spring *3* to press said strip toward the barrel. The ends of the barrel *D* extend into annular grooves *w* in the end walls or heads of the casing *A*.

There is a transverse socket in the barrel 70 *D* to receive a rocking bearing-block *E* with curved edges adapted to those of the sides of the socket and, if desired, with end trunnions 75 *4*, extending into recesses in the barrel. This block is slotted for the passage of the piston *C* and has recesses for packing-strips *5*, each 80 of which may be pressed toward the piston by a spring *6*. When the chamber *X* is used as a primary chamber, the inlet-port *7* is arranged to admit steam or other fluid under 85 pressure to the chamber *X* at a point at one side of the packing-strip *2*, so that when the piston has passed by said strip and beyond the port *7* the steam will act on the piston to turn the shaft *B* in the direction of the arrow, 90 Fig. 1, and will be confined in the part of the chamber between the piston and what I term the "abutment"—that is, the recess *y* where the barrel meets the curved wall *x* of the chamber *X*—the extent to which the barrel 95 enters the recess *y* tending to prevent leakage past the strip *2* at this point.

In Fig. 1 the exhaust-port *8* is shown in the end wall of the casing so arranged as to communicate with the interior of the barrel *D*.

An important feature of my invention consists in the provision made for the passage of steam or other fluid between the chambers *X* and *Z* past the barrel *D*. This provision consists, preferably, of a series of passages so arranged that when the piston moves in the direction of the arrow, Fig. 1, it does not open the first of said series of passages to the steam behind it until it has traversed about one-half rotation from the inlet-port *7*, from which 100 point the number of passages of said series 105 opened for the passage of steam will increase until the piston has reached approximately

the abutment. The series of these passages is therefore shown in the drawings as comprehending nearly one hundred and forty degrees of the barrel and as located on the opposite side of the barrel from the port 7. Theoretically the distribution of these passages would be in an arc of one hundred and eighty degrees between the outer edges of the extreme passages; but in the construction shown the barrel enters the recess in the casting for a purpose described hereinafter, so that this arc is lessened by the extent to which the abutment advances by this entrance of the barrel into said recess. Although the scope or field of this series of passages may be somewhat varied from that named it is nevertheless important to the efficiency of the engine that it should be approximated to such an extent that the fluid cannot be trapped as the piston approaches the contact-points of the barrel and casing or hub.

With the series of passages comprehending the extended scope of the piston-stroke shown, although the pressure of steam upon the piston will be applied to only a portion of the piston area during the movement of the piston in the direction of the arrow, Fig. 1, from the port 7 nearly to the first of the passages *t*, nevertheless from the time that the piston commences to open up said series of passages until it approaches the exhaust-port the pressure of the steam will be upon substantially the full piston area. In other words, as shown in Fig. 1, the pressure of the steam upon the piston as it moves in the direction of the arrow on the first stroke ahead will be upon the portion of the piston in the chamber X only for about one hundred and thirty degrees. It will then be exclusively within the chamber X upon substantially the whole of the piston for over ten degrees. It will then be upon substantially the whole of the piston, partly in the chamber X and partly in the chamber Z, for about one hundred and fifty degrees. It will then be upon substantially the whole area of the piston exclusively within the chamber Z for about forty degrees or more. For all strokes of the piston succeeding the first the residuum of pressure from the last preceding stroke will continue on the piston within the chamber Z until the piston commences to open the exhaust, which is at a point of the piston-stroke beyond the point at which it has opened the inlet-port 7 for the next succeeding stroke. Therefore in the regular running of the engine the portion of the piston-stroke when its whole area is not substantially under pressure will be limited to about ninety degrees. By full piston area I refer to the area corresponding substantially with the area of the piston in the chamber X at the point of maximum protrusion of the piston through the barrel D. The position individually of these

passages *t* is also important. In order that as the piston proceeds along the series there shall be no point at which any passage or passages shall admit the steam ahead of the piston either in the chamber X or the chamber Z, the position which they individually occupy is therefore radial to the center of the shaft B, as shown in the drawings, and the width of each individual passage is less than the width of the piston. In this way at no time in the operation is any passage open on opposite sides of the piston at the same time, and therefore there is no time in the operation when the steam can pass across the piston through any passage.

I have shown various forms in which the passages between the chambers X and Z may be constructed. Thus in the form shown in Figs. 1 to 7, inclusive, these passages are formed partially by notches *v* in the edges of the barrel and partially by the channels cut in the heads of the casing. In this form the steam passes around both ends of the barrel, though in certain instances it will answer to confine the passages to one end of the barrel. In Fig. 8 the passages *t* are shown as in pipes extending out through the head of the casing on one side of the barrel-groove therein and into a superheating-flue 57 and returning through the head of the casing on the opposite side of the barrel-groove therein. In Fig. 9 the passage *t* extends the same as in Fig. 8, excepting that it is formed wholly within the casting of the casing-head. In Fig. 10 the passage *t* is the same as in Figs. 1 to 7, inclusive, with the exception that it is wholly formed by a channel within the casing-head without any notches in the edge of the barrel.

The port 7 is controlled by a suitable valve, so that the inlet of the steam may be cut off at desired points of each stroke of the piston. The valve shown in Figs. 1 and 2 is arranged to run the engine anticlockwise with variable cut-off and clockwise with constant pressure throughout the stroke. The valve in Fig. 3 is arranged to run the engine in either direction with variable cut-off or with constant pressure throughout the stroke, starting at any point.

The valve consists of a casing 65, having a circular valve-chamber, within which is mounted a sleeve 10, within which is mounted a cylindrical valve member 12. The valve member 12 is constantly rotated in time with the engine by connection with the main shaft of the engine and contains the passage 66, whereby the steam-main 67 is in the position shown in Fig. 3 connected with and cut off from the port 7 at determinate times of the stroke. The sleeve 10 is oscillated by hand, and the passage 68 thereof places it within the power of the operator to connect the steam-main 67 either with the port 7 for going ahead or with the passage 69,

leading to the port 8, Fig. 5, for reversing at any point of the stroke. Thus it is within the power of the operator by utilizing the passage 68 to dominate the cut-off 66 and cause the engine to be run either under steam direct from the boiler or under expansion. By oscillating the sleeve 10 to an extent of ninety degrees until the passage 70 therein registers with the passage 67 the cut-off passage 66 will connect the passage 67 with the passage 69, and thus reverse the engine operating under the cut-off. 71 is an exhaust passage in the sleeve 10.

When the steam is cut off at any point of the piston-stroke, it will act expansively thereafter, and this action will for a great portion of the piston's traverse be upon the entire available area of the piston.

To permit the escape of condensed fluid in exhausting when the piston is moving in the direction of the arrow, Fig. 1, the port 8 has a tapering extension 14, which is continued to the lowest point within the barrel traversed by the piston in its rotation. It is intended in reversing to use entrance-port 7 as an exhaust and exhaust-port 8 as an entrance-port.

It will be seen that the piston during its rotation assumes different angles with respect to the barrel, which is permitted by the rocking bearing E, but without any leakage, as the pressure tends to seat such bearing in its grooved socket, while the strips 5 effectually pack the faces of the piston.

The packing of the piston where it passes through the barrel in some such manner as at the rocking bearing E is essential, because otherwise the steam-pressure would be equalized on both sides of the piston at some portion of the stroke corresponding to a dead-center. It is also necessary to provide a positive bearing for the piston when it passes through the barrel, because if there was the slightest play or lost motion the hammering at a rotation of several hundred revolutions a minute—the speed attained in actual practice—would soon destroy the parts. As the ends of the barrel extend into annular grooves, the bearing-faces of the barrel and grooves will wear evenly, thus avoiding the objections incident to the use of a rotatable barrel the ends of which bear on the inner side walls of the casing.

In reversing the engine in order to prevent trapping between the port 7 acting as the outlet-port and the abutment I provide a slight clearance-space 40, which communicates backward with the port 7 over the extremity of the piston.

In the construction shown in Figs. 3 to 6 the general arrangement and the construction of some of the parts correspond to those already described; but there are additional features, embodying principally packing

means (not shown in the other figures) and the use of a shaft having a hollow enlargement or hub, the chamber Y of which communicates with the exhaust-port. As shown the chamber Y has end ports s communicating with ports r, Fig. 5, of the casing leading to the exhaust-port 8.

The hollow hub has a port n at one side, and the series of channels t is so arranged and the port n in the hollow hub of the shaft is of such dimensions that in reversing the steam cannot be confined between the piston and the periphery of the hub until the piston has traveled to such an extent that a substantial piston area will be exposed within the barrel to the inflowing steam—that is, the end a of the port n will not pass the terminal channel until the piston has traveled so far in the direction of the arrow b, Fig. 3, that a substantial area is exposed between the hub and the inner face of the barrel and sufficient reversing power is insured. Before the end a of the port n closes the terminal channel the steam can pass through the latter to the piston outside the barrel, where sufficient area is exposed to secure the necessary power.

The piston is recessed to receive an edge packing-blade 15 with scarfed ends meeting those of side packing-blades 16, and the edge blade 15 is held in place by pins 17, which when the blade is in place occupy the positions in the horizontal parts of L-shaped slots 18 in the sides of the recess, the insertion and removal of the blade being effected by shifting the blade to bring the pins into line with the radial parts of said slots. As the slots do not extend through the walls of the piston, the pins cannot escape under any conditions. As the trunnions 4 of the rocking bearing E are of a diameter approximating the thickness of the bearing, I cut away the side edges of the piston, as shown in Fig. 6, to increase the body of metal between the inner ends of the trunnions and the ends of the bearing, and I extend the packing-strips 5, which have slotted ends, only to those bevels, and pack these parts of the piston by U-like packing-pieces 19, whose ends meet those of the strips 5, enter the slots in same, and the cross portions of which bear on the outerfaces of the side strips 16. The ends of the enlargement 1 of the shaft have annular recesses to receive annular packings 20, and the side strips 16 have at their lower ends lips 21, Fig. 4, which extend inward and meet the peripheries of said annular packings. The parts back of the said strips and pieces 15 16 19 are socketed to receive springs 23, which carry the strips toward the bearing-faces. As there is no tendency to force these strips inward, the said springs are light and there is little effect in increasing friction or wear. I thus effectually prevent the passage of steam past any of the edges of the piston or of the enlargement 1 of the

shaft, and it will be seen that in general principles all of the packing means are of conventional character, readily machined to proper bearing shape, and that they will wear evenly and regularly and maintain tight joints. To securely pack the periphery of the barrel and compensate for wear at this point, I make use at each side of an annular ring or packing 26, which may be in sections and which has a beveled or tapering face *m*, adapted to a like face of the casing, so that by forcing the ring inward the joint may be packed and wear compensated for. The packing may be forced inward and secured in any suitable way; but, as shown, set-screws 27, adjustable from the outside of the casing, are used for this purpose. Preferably this ring forms the outside bearings of the barrel, as shown; but it might be used on the inside. This ring 26 is split, and the joint between the sections is opposite the strip 2, so that leakage at this point is not material.

It will be evident that if the engine was reversed (see Fig. 3) any condensed liquid or lubricating-oil would after the piston passed the port 7 be confined in the contracted recess between the piston and the converging faces of the casing and barrel, which would result in hammering or straining the parts. To prevent this, I provide a channel 40 in the inner wall of the casing extending from at or near the port 7 toward the abutment, and when the piston on the reverse motion moves downward any liquid in the said space will flow upward through the channel and escape.

As shown in Fig. 4, the barrel C is in two sections with a mortise joint *j*. This facilitates construction and the introduction and securing of the rocking bearing-block E and tends to make it retain its original shape under all temperatures. These sections are bolted together by suitable cross-bolts. (Not shown.)

The pressure is maintained on the full area of the piston outside of the barrel from the time the piston passes the inlet-port 7, acting under the volume of steam then admitted until it has traversed about half its stroke. It thereafter begins to uncover the first channel *t* to permit the steam to be then discharged into the interior of the barrel. Thereafter there is also pressure on the piston area within the barrel until the piston passes the exhaust-port 8, as in Fig. 1 or in the construction shown in Fig. 3, until the hub 1 has rotated to an extent to put the chamber X back of the piston in connection with the port *n*, as in the position of Fig. 3, when the steam will pass from said chamber through the port *n* to the exhaust.

It will of course be understood that the full boiler-pressure of the steam may be used throughout the rotation or the plug 12 of the valve device may be shifted to cut off at any

point of the rotation, the steam acting exclusively thereafter.

The recess or depression *y* in the casing and the position of the barrel therein not only secure a greater contact area and better sealing and abutment at this point, but is most important in causing the edge of the piston to occupy a position within or back of the outer face or periphery of the barrel when opposite the packing-strip 2, as shown in Fig. 1, this resulting from the said edge moving in a circle concentric with the shaft and corresponding to the curved wall of the casing, while the periphery of the barrel projects into the recess *y* beyond this circle. This prevents the edge of the piston and its sealing-strip from making contact with the sealing-strip 2. This is most important, as heretofore in other engines the contact of the piston and strip 2 has resulted in destroying the latter and impairing the efficiency of the engine.

As there is a series of channels *t* there is no throttling of the steam, the number of uncovered channels increasing as the piston travels and the steam expands.

By providing the inlet-port 7 in the casing so as to admit steam first outside the barrel I avoid introducing superheated steam (when used) at the shaft-bearing when running ahead.

To compensate for wear of the rocking bearing E, I in some cases provide the edges thereof with adjustable shims 61, Fig. 11, which can be adjusted to maintain the desired contact of bearing-faces. As shown, each shim is a curved wedge-shaped strip secured by bolts 62 to the body of the bearing, and to prevent slippage the contacting faces of the body and shims have parallel interlocking ribs and recesses.

While I herein refer to the use of steam, I do not wish it to be understood that my apparatus is one adapted for such use only, and I wish the term to be understood as practically including any suitable vapor or fluid.

In Figs. 12 and 13 I have shown my improved apparatus as used for transmitting motion to a fluid as in pumping. The apparatus is of substantially the same construction as the engine shown in Figs. 3 and 4, with the following exceptions: All of the passages for the fluid are enlarged and where necessary the parts are enlarged to accommodate such enlargement of the passages. The valve 10 12 is omitted. Where it is necessary to hold the fluid against back pressure a check-valve 60, closing toward the pump, is used.

Without limiting myself to the construction and arrangement shown, I claim—

1. In a rotary engine, having a barrel eccentrically arranged within the casing, a central shaft and a piston extending therefrom through the barrel to the casing, a series of

passages arranged to connect the chambers inside and outside the barrel, and to be successively fully closed and then opened on the passage of the piston.

5 2. In an apparatus for the conversion of energy, in combination, a cylinder, an eccentric barrel, a shaft, a piston extending from the shaft through the barrel, inlet and outlet ports and a series of passages between the 10 chambers interior and exterior to said barrel arranged radially in respect to the center of the shaft as set forth, whereby the pressure is applied to only part of the piston area during part of the stroke and is upon the full piston area during another substantial part of the stroke.

3. In a rotary engine, in combination, a cylinder, an eccentric barrel, a shaft, a piston extending from the shaft through the barrel, 20 inlet and outlet ports, passages between the chambers interior to and exterior to said barrel arranged radially in respect to the center of the shaft as set forth whereby the pressure is applied to only part of the piston area during 25 part of the stroke and is upon the full piston area during another part of the stroke and means for cutting off the steam to secure its expansive action upon the full area of the piston.

30 4. In a rotary engine having a cylinder, an eccentric barrel, a shaft, and a piston extending from the shaft through a packed opening of the barrel, inlet and outlet ports and channels arranged radially to the center 35 of the shaft as set forth, whereby the pressure is upon only part of the piston area during the first half of its traverse and is uniformly upon the full piston area during another substantial part of the traverse.

40 5. In a rotary engine having a casing, an eccentric barrel, a shaft and piston extending therefrom through the barrel, ports communicating with the chambers outside of and within the barrel, channels whereby the 45 steam may pass from one chamber to the other, and means whereby the steam may be admitted directly from the supply to either the port communicating with the outside chamber or that communicating with the inside chamber at any point of the stroke.

6. The combination with the eccentric barrel, a shaft and a piston extending therefrom through the barrel and having its side edges beveled substantially as described.

55 7. The combination in a rotary engine of the casing, having a circular chamber and sides with annular grooves, eccentric barrel extending into said grooves, tapering packing and bearing rings surrounding the periphery of the barrel within the grooves, the 60 inclined faces of the rings adapted to inclined faces of the grooves, and means for moving the rings inward.

8. The combination with the casing and 65 eccentric barrel of a rotary engine, of a shaft

carrying a piston extending through the barrel and provided with a hollow enlargement within the barrel, the said enlargement having a port in its periphery and a series of passages radial to the shaft through which the 70 steam can pass between the outside chamber and said port, and the casing having an exhaust-port communicating with the chamber within the enlargement.

9. The combination with the casing and 75 eccentric barrel of a rotary engine, of a shaft carrying a piston extending through the barrel and provided with a hollow enlargement within the barrel, the said enlargement having a port in its periphery, and the casing 80 having channels or passages affording a communication between the chambers within and outside the barrel, and an exhaust-port communicating with the chamber within the enlargement.

85 10. The combination with the casing having inlet and exhaust ports, and eccentric barrel, of a shaft carrying a piston extending through the barrel and provided with a hollow enlargement or hub within the barrel, 90 and a series of channels affording communication between the chambers inside and outside of the barrel, the said hub having a port arranged to afford a communication between the hub and the chamber outside the 95 barrel until a material area of the piston is exposed within the barrel.

11. The combination in a rotary engine, of a casing, eccentric barrel, shaft, and piston extending through a sealed opening of the 100 barrel, inlet and outlet ports, and passages arranged radially for approximately one-half of the piston's travel to secure the pressure of the steam on the piston area outside the barrel during a part of the traverse, and a 105 pressure upon the piston area at the same side of the piston both outside of and within the barrel for another part, and only within the barrel for another part of the traverse.

110 12. The combination in a rotary engine, of a casing, eccentric barrel, shaft, and piston extending through a sealed opening of the barrel, inlet and exhaust ports, and passages arranged radially for approximately one-half of the piston's travel to secure the pressure 115 of the steam on the piston area in the primary chamber outside of the barrel as the piston passes the inlet-port and during part of the traverse, and only on the piston area within the barrel during another part of traverse and a pressure upon the piston both outside of and within the barrel for another part of traverse and until the piston passes the inlet and the engine exhausts.

120 13. The combination with the piston of a 125 rotary engine recessed at the edge, of a packing-strip within the recess provided with pins 18, and L-shaped grooves in the sides of the recesses receiving said pins.

14. The combination with the shaft and 130

piston of a rotary engine, of an eccentric barrel consisting of two rings or sections with meeting edges, and a recess formed partly in each section and a rocking bearing having a 5 recess for the passage of the piston fitted to rock in the recess formed in said sections.

15. In an apparatus for the conversion of energy, in combination, a casing, an eccentric barrel, a shaft, a piston extending therefrom through the barrel, ports communicating with the chambers interior and exterior to said barrel and a plurality of channels of communication between the said chambers, the distance between the outer edges of the 15 first and last channels comprehending about one-half the circumference of the barrel, said channels arranged to secure a working pressure within the parts of said chambers behind the piston at all points of the stroke.

20. 16. In an apparatus for the conversion of energy, in combination, a casing, an eccentric barrel, a shaft, a piston extending therefrom through the barrel, ports communicating with the chambers exterior to and interior to 25 said barrel and a series of passages between said chambers through which the fluid passes in a direction backwardly inclined to the radii of the barrel.

17. In an apparatus for the conversion of 30 energy in combination, a casing, an eccentric barrel, a shaft, a piston extending therefrom through the barrel, ports communicating with the chambers exterior to and interior to said barrel, a series of passages between said 35 chambers through which the fluid passes in directions increasingly inclined to the radii of said barrel.

18. In an apparatus for the conversion of energy, in combination, a casing, a shaft concentric with the interior of said casing, an eccentric circular barrel forming peripheral contact with the interior of said casing, a piston carried by the shaft and extending from said shaft through the barrel, a port near 45 said contact for the chamber exterior to said barrel, a port near the shaft for the chamber interior to said barrel and a series of passages radial to the axis of the shaft connecting said chambers and extending substantially from 50 the point of said barrel nearest said shaft to the point of said barrel nearest said casing.

19. In an apparatus for the conversion of energy, in combination, a cylinder, an eccentric barrel, a shaft, a piston extending from 55 the shaft through the barrel, inlet and outlet ports in the casing and passages partly in the edges of the barrel and partly in the casing adjacent thereto arranged to permit steam to pass from the outside to the inside of the 60 barrel.

20. In an apparatus for the conversion of energy, in combination, a cylinder, an eccentric barrel, a shaft, a piston with beveled edges extending therefrom through the barrel, a rocker-bearing E between the piston 65 rel,

and the barrel, packing-strips therein bearing on the faces of the piston and U-shaped packing-pieces 19 fitting the side edges of the piston.

21. In an apparatus for the conversion of energy, in combination, a cylinder, an eccentric barrel, a concentric shaft, a piston extending from the shaft through the barrel, inlet and outlet ports to the chambers within and without said barrel and a series of passages connecting said chambers and means whereby the fluid passing through said passages is heated. 70

22. In an apparatus for the conversion of energy, in combination, a casing, a shaft, an eccentric barrel the ends of which abut in grooves in the heads of said casing, tapered split rings surrounding said barrel within said grooves and means for adjusting the same; the faces of said rings presented to said 85 barrel being substantially cylindrical.

23. In an apparatus for the conversion of energy, in combination, a cylinder, a shaft, an eccentric barrel forming peripheral contact with the interior of said cylinder, a piston extending from said shaft through said barrel, a series of passages between the chambers exterior and interior to said barrel, a port for said interior chamber, a port in the periphery of said exterior chamber near said 95 barrel contact and a clearance-space, 40, extending from said peripheral port toward said contact.

24. In an apparatus for the conversion of energy, in combination, a cylinder, a shaft, an eccentric barrel, a piston carried by said shaft and extending through said barrel, a hollow boss carried by said shaft and containing ports at its periphery and head and a steam-box 8 with which said head port communicates extending substantially around the shaft. 100

25. In a rotary engine, in combination, a cylinder, a shaft, an eccentric barrel, a piston extending from the shaft through the barrel, 110 passages radial to the axis of the shaft connecting the chambers interior and exterior to said barrel, ports respectively in said exterior and interior chambers, supply and exhaust passages connected with said ports and unitary valve mechanism whereby the connection between said ports and said passages may be reversed. 115

26. In a rotary engine, in combination, the cylinder, the shaft, a cylindrical barrel, a piston extending from the shaft through the barrel, passages connecting the chambers interior and exterior to said barrel, ports for said chambers, a valve-chamber, passages leading from said ports to said valve-chamber, a constantly-rotated cut-off-valve member 12, connections whereby the same is rotated by the engine and an intermittently-oscillated valve member 10 provided with a by-pass passage around the cut-off. 120 125 130

27. In a rotary engine, in combination, the cylinder, the shaft, a cylindrical barrel, a piston extending from the shaft through the barrel, passages connecting the chambers interior and exterior to said barrel, ports for said chambers, a valve-chamber, passages leading from said ports to said valve-chamber, a constantly-rotated cut-off-valve member 12, connections whereby the same is rotated by the engine and an intermittently-oscillated valve member 10 provided with a by-pass passage around the cut-off and means whereby said valve member 10 may be moved to introduce said by-pass passage between the steam-main and either port.
28. In a rotary engine, in combination, a cylinder, an eccentric barrel, a shaft, a piston extending from the shaft through the barrel, inlet and outlet ports, passages between the chambers within and without the barrel arranged substantially as set forth whereby the pressure is applied to only part of the piston area during part of the stroke and is upon substantially the full piston area during another part of the stroke, means whereby the steam may be cut off during the stroke and means independent of the cut-off whereby the boiler-pressure may be admitted to the piston at any point of the stroke.
29. In a rotary engine, in combination, a cylinder, a shaft, an eccentric barrel, a piston extending from said shaft through said barrel, a series of passages radial to the axis of the shaft connecting the primary and secondary chambers on opposite sides of said barrel and arranged as set forth whereby the number of said passages transferred to the low-pressure side of said piston in the secondary
- chamber increases in proportion substantially as the area of the piston in the said secondary chamber increases.
30. The combination with an engine having a casing, radial piston-barrel and a rocking bearing in the barrel for the passage of the piston, of shims adjustable at the edges of the bearing to compensate for wear.
31. The combination with an engine having a casing, radial piston-barrel and rocking bearing in the barrel for the passage of the piston, of curved wedge-like shims and means for connecting them adjustably to the edges of the bearing.
32. The combination of an engine having a casing, radial piston-barrel, and rocking bearing in the barrel for the passage of the piston, of curved wedge-like shims and means for connecting them adjustably to the edges of the bearing, said shims and edges having interlocking ribs.
33. In a device for receiving and transmitting energy, the combination of a shaft, an eccentrically-located barrel, a piston extending from said shaft through said barrel, a cylinder with a recess γ into which the said barrel extends, chambers exterior and interior to said barrel, and a series of passages connecting said chambers through which the fluid passes inclined in a direction at angles to the radii of said barrel.
- In testimony whereof I have hereunto signed my name in the presence of two subscribing witnesses.
- EDWIN TAYLOR.
- Witnesses:
- CHARLES E. FOSTER,
J. J. McCARTHY.
